United States Patent Office.

W. O. HICKOK, OF HARRISBURG, PENNSYLVANIA.

Letters Patent No. 82,884, dated October 6, 1868.

IMPROVEMENT IN PAPER-RULING MACHINES.

The Schedule referred to in these Letters Patent and making part of the same.

TO ALL WHOM IT MAY CONCERN:

Be it known that I, W. O. HICKOK, of Harrisburg, in the county of Dauphin, and State of Pennsylvania, have invented a new and useful Improvement in Paper-Ruling Machines; and I do hereby declare that the following is a full, clear, and exact description of the construction and operation of the same, reference being had to the accompanying drawings, making a part of this specification, in which—

Figure 1 is a perspective view of one of the said improved machines broken away across its middle in order to narrow the figure.

Figure 2, a vertical transverse section of part of the same cut through the centres of the turning points of the pen-beam; and

Figure 3 a vertical longitudinal section of the sliding standard, which supports the further end of the pen-beam.

Like letters of reference indicate the same parts when in the different figures.

Although the pen-beam of paper-ruling machines has been supported upon standards and bearings made adjustable by means of slots and screw-nuts, or by means of thumb-and-finger screws, in combination with slides and jam-nuts, for the purpose of enabling the attendant to adjust the pen-beam with accuracy and facility, to suit defects in the form of the paper, many of the reams in a lot of paper being often trimmed or cut at irregular angles, yet the different devices heretofore produced for the purpose are still more or less defective, especially in that they do not provide against the very objectionable binding or strained result upon the beam and its bearings, arising from the movement of the nearer one of the supports of the pen-beam, while the other or further one is stationary, relative conditions which are almost constant.

The object of my improvement is to avoid this objection; and my invention consists in the construction and application of a perforated ball in combination with a sliding stem, so as to afford a ball and sliding joint, for the further end of the pen-beam, substantially as hereinafter described.

My invention also consists, in combination with the said ball and sliding joint, the employment of a solid-ball joint, for supporting the nearer end of the said pen-beam, substantially as hereinafter described; and my invention also consists, in combination with the said two ball-joints, the application of the standards, so that they can be slid longitudinally along on the table or frame of the machine with greater accuracy and facility as the required adjustments of the pen-beam may from time to time require during the operation of the machine, substantially as hereinafter described.

Referring to the drawings, A is the pen-beam; B B', the sliding standards; C C', fixed supports for the sliding standards; D D', the ball-joints; E E', stems, which connect the respective ball-joints and standards to the two ends of the pen-beam; and F, sections representing the table or frame of the machine.

The standard B consists of a post, b'', having a flat foot, b''', whereby it is supported in a vertical position, and so that it can be slid along backward and forward on its base, C, which is fixed permanently to the frame, F, of the ruling-machine.

Projecting on the front side of the post b'' there are two fixed lugs, b⁴ b⁵, through both of which a thumb-and-finger screw, g, is secured, so that it can be rotated without screwing in the said lugs. Between the lugs b⁴ b⁵ a block, g', is fitted to slide accurately up and down the post b'', when the screw g, which screws through it, is rotated accordingly. Transversely through this sliding block g', another thumb-and-finger screw, g'', works, and which is fitted with a jam-nut, g''', at the outer side of the post b'', while its inner end is finished with a ball, g⁴, (see fig. 2.)

The rear end of the base, C, of the post b'' has an upright, c'', in which a thumb-and-finger screw, c''', is secured in a horizontal position by a head and jam-nut thereon, so that it can be rotated without screwing in the upright, c'', and on the slide b'' there is a corresponding upright, b⁶, through which the said screw c''' is caused to move the slide in adjusting the standard B', (see fig. 1.)

On that end of the pen-beam A, which connects with the ball g⁴, there is fixed a two-part clamp, a' a'',

the part a'' being detachably secured to the part a' . Between these two parts a spherical cavity is made for the reception of the ball g' on the end of the screw g'' , so that the said cavity, with the said ball on the end of the screw g'' , will form together the ball-joint D, a sufficient space being made around between the screw-stem and the outer opening of the cavity to allow the required motion in the joint, as will be hereinafter referred to.

The standard B' is supported in a vertical position, and so that it can be slid backward and forward in a fixed base, C', by means of a screw, c''' ; precisely in the same form and manner as upright, B. Projecting from the upper end of the post b'' thereof there is a boss, b' , through which a screw, H, is caused to slide accurately up and down by means of a thumb-and-finger nut, h' , above the boss b' , a jam-nut, h'' , being applied below the boss for the purpose of fixing the said screw when necessary.

The lower end of the screw H has fixed to it a two-part clamp, h''' , the two parts of h''' being detachably secured together by screws. Between the two parts of the clamp h''' there is a spherical cavity, in which a perforated ball, h' , is accurately fitted to rotate, and, fixed to the further end of the pen-beam A, there is a projecting stem, a''' , which accurately fits through the perforation in the ball h' , yet so that the said stem can be slid along within the ball, sufficient space being made around between the open edges of the spherical cavity and the stem to allow the required motion of the ball-joint, as will hereinafter be referred to.

The projecting stem a''' is fixed in a boss on a plate, a' , which plate is fixed on the end of the beam A, substantially as represented in fig. 2.

It will be readily seen that, by means of the ball-joints D D' and sliding standards B B', constructed and arranged in combination with the pen-beam and the frame or table of the machine, as described, the said pen-beam, with its pens attached, can be instantly adjusted with facility and perfect accuracy, to suit any inequality in the paper passing under them, and without any binding or straining, because a rotary motion given to the screw g'' will give an exact longitudinal motion to the pen-beam. A like rotary motion given to either of the screws g and h will give an exact vertical motion to either end of the pen-beam. A like rotary motion given to either of the screws, c'' , of the slides, will give an exact horizontal motion to the said beam, and therefore, the beam being suspended by the ball-joints D D', any movement required in the said pen-beam can be instantly and accurately given with facility, and without causing any binding or straining whatever at any part of the beam.

It will also be seen that the manner in which the axis or stem, a''' , of the further end of the pen-beam is applied thereto, is an improvement of importance, as it affords, not only a more substantial axis, but admits of greater accuracy in its application to the beam.

Having thus fully described my improvement, what I claim as new therein of my invention, and desire to secure by Letters Patent, is confined to the following, viz:

1. I claim suspending the pen-beam of a paper-ruling machine by means of the ball-joints D and D', in combination with sliding standards, B and B', operating together, substantially as and for the purpose described.
2. I claim the ball-joint D', consisting of the socket h' and the perforated ball therein, in combination with the stem a''' on the end of the pen-beam, the said parts operating together substantially in the manner described.
3. I claim, in combination with the pen-beam A and sliding ball-joint D', the solid ball-joint D, consisting of the spherical cavity within the clamp $a' a''$ on the end of the pen-beam A, and the solid ball g' on the end of the screw g'' , the said parts being constructed and arranged to operate substantially as and for the purpose described.
4. I claim, in combination with a pen-beam, A, suspended upon the ball-joints D and D', as described, the sliding standards B and B', operated by means of their respective screws $c''' c'''$, substantially as and for the purpose described.
5. I claim, in combination with the pen-beam of a ruling-machine, the stem a''' , constructed and applied substantially as and for the purpose described.

W. O. HICKOK.
